UNITED STATES PATENT OFFICE

2,564,745

SOIL DISPERSING APPARATUS

Adolph M. Wintermyer, Washington, D. C., assignor to United States of America as represented by the Administrator of the Federal Works Agency

Application July 2, 1948, Serial No. 36,796

2 Claims. (Cl. 259—95)

(Granted under the act of March 3, 1883, as amended April 30, 1928; 370 O. G. 757)

1

The invention described herein may be manufactured and used by or for the Government of the United States for governmental purposes without the payment to me of any royalty thereon in accordance with the provisions of the Act of April 30, 1928 (Ch. 460, 45 Stat. L. 467).

This invention relates to improvements in "Soil Dispersing Apparatus," for use in the mechanical analysis of soils for the purpose of determining their suitability for use in the construction of highways, bridges, buildings and other structures.

The invention has for its object to provide a soil dispersing apparatus in which air under controlled pressure is employed as a dispersing medium to reduce the abrasion on the soil mineral particles to a minimum and to increase the degree of dispersion.

With these and other objects in view, the invention consists in the novel construction of the apparatus and particularly, in the novel construction of the agitating arrangement, all of which will first be fully described and afterwards specifically pointed out in the appended claims.

Referring to the accompanying drawing which illustrates a preferred embodiment of the invention,

Fig. 1 is a vertical sectional view through the soil dispersing apparatus.

Fig. 2 is a top plan view of the same.

Fig. 3 is a horizontal sectional view through the apparatus taken on line 3—3 of Fig. 1, and

Fig. 4 is a fragmentary elevation of the top portion of the cylindrical container of the apparatus.

Like numerals of reference indicate the same parts throughout the several figures, in which:

1 indicates the cylindrical casing of the apparatus to which is connected a head 2 having a depending annular flange 3 which fits snugly inside of the casing 1 and is removably secured thereto by means of pins 4 operating in bayonet joints 5 as shown in Figs. 1 and 4.

Suspended from the head 2 by a plurality of rods 6 is the semi-spherical baffle or spatter plate 7 of a slightly less external diameter than the inside diameter of the cylindrical casing 1, so as to provide an annular space 8 between the baffle 7 and the cylindrical casing, while a handle 9 is provided centrally of the head 2, in which an air vent 10 is provided.

Referring to the bottom of the apparatus, it will be seen that the cylindrical casing 1, is externally threaded at 11 to receive the threaded base 12, which base 12 is itself externally threaded at 13 to receive the threaded bottom cap 14.

This cap 14 is provided near its top edge with

2

an internal annular chamber 15, at which is connected a friction nipple 16 to receive a flexible air tube or hose (not shown) leading from a source of controlled air pressure (not shown) as will be clearly understood from an inspection of Fig. 1 of the drawing.

Threaded at 17 into the base 12 at points registering with the annular chamber 15 in the bottom cap 14 are preferably six downwardly inclined air nozzles or tubes. Four of these nozzles or tubes indicated by the numeral 18 are set at considerable angularities with respect to each other, while two of them which are set opposite to each other and indicated by the numeral 18a are very slightly angular to each other as shown in Fig. 3, while there is set in the center of the curved bottom 19 a substantially cone shaped button 20 of harder material secured therein by a screw 21 so as to permit its removal if it becomes worn in use. The curvature of this button 20 blends with the curvature of the bottom 19 so that there is no break or interruption to the continuity of the entire bottom surface, which, if present would tend to interfere with the smooth and efficient operation of the apparatus, which will now be described.

In this art, the device as just described is designated as a "dispersing cup." Into this is introduced the soil-water-electrolyte mixture, the total volume of which should preferably not exceed 250 ml. of which approximately 20 ml. is of a suitable electrolyte such as sodium metasilicate having a density of 3° (degrees) Bé. (Baumé).

Air is now introduced at suitable pressure into the apparatus and enters it through the friction nipple 16 from whence it circulates around the internal chamber 15 in the base 12 and enters the air nozzles or tubes 18 and 18a. The air which passes into the mixture from the nozzles or tubes 18 imparts a swirling motion to the mixture, while the slight angularity at which the two opposed tubes 18a are set causes the two currents set up by the two opposed jets of air to just pass each other and sweep the pointed central portion of the cone 20 and prevents the accumulation of material at that central point. It will be noted that the air tubes are slanted inwardly of the base with their inner ends in close proximity to the central cone so that the latter is thoroughly washed by strong currents for preventing the undesired central accumulation of material.

According to the nature of the soil, the dispersion may be continued for from 5 to 15 minutes, the dispersion of the smaller sized particles being obtained by the agitation produced by the air

passing through the suspension, while at the same time the coarser particles are freed from adhering material and abrasion is held to a minimum.

The air which enters the apparatus and provides the agitation passes out through the vent 10 in the head 2, while the mixture is confined in the device by the presence of the baffle 1.

Having thus described the invention, what I claim as new and desire to secure by Letters Patent of the United States is:

1. Soil dispersing apparatus which includes a cylindrical casing, a vented head, means for removably attaching the head to the casing, a baffle suspended within the casing from the head, a base having a curved bottom secured to the casing, a bottom cap secured to the base and provided with an internal annular chamber adapted to receive air from a source of supply, a plurality of air nozzles in the base and communicating with the internal annular chamber in the bottom cap, a substantially conical shaped button removably secured in the base and conforming to the curvature of the bottom thereof, said air nozzles being downwardly inclined, certain of which are set at substantial angles to one another so that the air therefrom will impart a swirling motion to the contents within the apparatus and certain of which are set opposed to and at slight angles to each other to sweep the pointed central portion of the substantially conical button and prevent the accumulation of material thereat.

2. Soil dispersing apparatus which includes a cylindrical container having a base and a vented top, a baffle within the container adjacent the vented top, a curved bottom in the base, a bot-

5 tom cap secured to the base and provided with an internal annular chamber adapted to receive air from a source of supply, a plurality of air nozzles in the base and communicating with the internal annular chamber in the bottom cap, the central surface of the curved bottom being substantially cone shaped, said air nozzles being downwardly inclined, certain of which are set at substantial angles to one another so that the air therefrom will impart a swirling motion to the contents within the apparatus and certain of which are set opposed to and at slight angles to each other to sweep the central conical surface of the bottom and prevent the accumulation of material thereat.

ADOLPH M. WINTERMYER.
